Specification for Design.

Patented July 13, 1920.

Application filed April 5, 1920. Serial No. 371,492. Term of patent 14 years.

To all whom it may concern:

Be it known that I, HARRY C. AATHERLY, a citizen of the United States, and resident of the city and county of San Francisco and State of California, have invented a new, original, and ornamental Design for a Lamp-Stand, of which the following is a specification, reference being had to the accompanying drawings, forming a part thereof.

In the drawing:

Fig. 2 is a side elevation of the lamp stand.

What I claim is:

The ornamental design for a lamp stand substantially as shown.

In testimony whereof, I have hereunto set my hand this 25th day of March, 1920, in the presence of the two subscribed witnesses.

HARRY C. AATHERLY.

Witnesses:

CARLOS P. GRIFFIN,
J. E. AATHERLEY.
